UNITED STATES PATENT OFFICE.

EDWARD A. ESCHINGER, OF PHILADELPHIA, PENNSYLVANIA, ASSIGNOR OF ONE-HALF
TO JOEL G. CLEMMER, OF PHILADELPHIA, PENNSYLVANIA.

TALKING-MACHINE.

1,301,787.

Specification of Letters Patent. Patented Apr. 22, 1919.

Original application filed June 16, 1917, Serial No. 175,082. Divided and this application filed May 6, 1918.
Serial No. 232,966.

To all whom it may concern:

Be it known that I, EDWARD A. ESCHINGER, a citizen of the United States, residing at Philadelphia, in the State of Pennsylvania, have invented a certain new and useful Improvement in Talking-Machines, whereof the following is a specification, reference being had to the accompanying drawings.

My invention relates to sound recording and reproducing machines, including gramophones and graphophones; and particularly feed mechanism for sound boxes of such machines adjustable to automatically repeat their coöperation with a given sound record, 15 at the will of the operator.

As hereinafter described, my invention is specifically adapted for such machines arranged to coöperate with flat disk records, and having sound conducting tubular arms 20 or horns which move with the sound boxes, and are so constructed and arranged that repetition of the coöperation of the sound box with any given record is consequent upon such movement, to an adjustably predetermined extent.

This is a division of my application Serial 175,082 filed June 16, 1917, for Letters Patent of the United States, showing forms of my invention as respectively embodied in a 30 graphophone and in a gramophone and I find it convenient to illustrate and describe the form of my invention herein claimed in connection with a gramophone of the type known commercially as a "Victor talking 35 machine." However, it is to be understood that I do not desire to limit myself to such specific embodiments of my invention, which includes the various novel features of construction and arrangement hereinafter more 40 definitely specified.

It may be observed that although the embodiment of my invention chosen for illustration herein is specifically different from the form of my invention shown embodied in a graphophone in my original application, and specifically claimed therein, they each include means to variably predetermine the initial and terminal positions of the respective sound boxes with reference to given 45 sound records, in combination with a single rotary cam constructed and arranged to automatically lift the sound box from coöpera-

tive relation with the record when it reaches a variably predetermined terminal position and to then return the sound box to its initial position and again lower it into co-operative relation with the record; said cam having the capacity to shift said sound box, throughout the maximum range of its movement, by frictional engagement with a cam 55 plate carried with the sound box, but its effective capacity is adjustably variable in accordance with variations in the extent of different sound records.

In the drawings; Figure I is a plan view 65 of the Victor gramophone aforesaid having a convenient embodiment of my invention in connection therewith. Fig. II is a side elevation of said machine shown in Fig. I. Fig. III is a full size plan view of the automatic 70 feed mechanism indicated in Figs. I and II, and Fig. IV is a left hand side elevation of said mechanism. Fig. V is a sectional view of said mechanism, taken on the line V in Fig. III. Fig. VI is a fragmentary sectional 75 view, taken on the line VI in Fig. III.

In said figures: 1 is a casing inclosing a gramophone including the record turn table 2 arranged to be turned by the motor 3 which is only indicated in dotted lines in Fig. II 80 but is mounted upon the underside of the casing top 4 which is detachably rigidly secured on said casing 1. The sound box 5, which is carried by the tubular tone arm 6, includes a vibratory diaphragm and carries 85 the stylus 7, indicated in Fig. II, arranged to traverse a groove in a record 9 on said turn table 2 and automatically shift said box toward the axis of said table. The amplifying horn 10 is rigidly connected with said 90 casing 1 but is pivotally connected with said tone arm 6 at 11.

The collar 12, which is detachably secured upon said horn 10 by the set screw 13, carries the adjustable initial stop lever 14 which is arranged to be manually secured in adjusted position by the set screw 15 shown in Figs. I and III. Said lever 14 rests upon the flange 16 of said collar 12 which is conveniently graduated as indicated at 18 in Fig. III so as to be traversed by the index lug 19 on said lever 14; whereby the position of said lever may be accurately determined so as to limit the initial position of

said box 5 in coöperation with said record 9 at the outer limit of its movement with respect to the axis of said table 2.

As said sound box is carried across said record 9 in coöperative relation therewith and toward the axis of said table 12, said tone arm 6 is swung in the direction of the arrow indicated in Fig. I; its terminal position being indicated by the dash lines in that figure corresponding with the terminal position of said sound box 5 with reference to said record 9, and the adjustable terminal stop lever 22 is arranged to variably limit the terminal position of said box 5 by variation in the extent of the stop arm 23 of said lever 22 which, as indicated in Figs. III to V inclusive, is a screw having a milled head 24 which serves as an index in its movement with respect to the graduated arm 25 on said lever 22. Said lever 22 is split to receive said stop arm 23 which it resiliently engages to prevent accidental displacement thereof. Said lever 22 is fulcrumed upon the screw 27 in the bracket 28 which is rigidly connected with the base plate 29 as indicated in Fig. III. The arm 30 of said lever 22 extends through the slotted end of the detent lever 31 as indicated in Fig. IV, so that when said sound box is carried to its terminal position said detent lever will be operated to release the spring lever 32 which it normally detains in the position shown in Figs. III and IV, and thereby initiate the operation of the automatic feed mechanism in connection with the gear 34 which is continuously turned during the operation of said gramophone by the means indicated in dotted lines in Fig. II, including the shaft 35 which carries said gear 34 and is journaled in the bracket 36 rigidly connected with said casing top 4. Said shaft 35 carries at its lower end the bevel gear 38 engaging the bevel gear 39 on the shaft 40 of the motor 3.

Said spring lever 32 is fulcrumed on the screw 43 engaging said base plate 29 and is connected by the spring 44 with the clutch shifting lever 45 which is fulcrumed on the screw 46 engaging said plate 29. As indicated in Fig. III; said spring 44 is under longitudinal tension and traverse flexion between said levers 32 and 45, and the construction and arrangement is such that when said detent lever 31 releases said spring lever 32; said levers 32 and 45 are respectively snapped in the directions indicated by the arrows marked thereon in Fig. III, (by the longitudinal collapse and horizontal flexure of said spring 44, which tends to straighten itself; supplemented by the consequent momentum of said lever 32,) to thrust the bevel gear 48 into engagement with said bevel gear 34 being turned by the motor 3. Said gear 48 is rigidly connected with and carried by the cam sleeve 50 which is mounted to slide

upon the stationary stud shaft 51 which is rigidly connected with said collar 12 as indicated in Figs. III and IV. However, in the normal idle position shown in Figs. III to VI inclusive, said sleeve is prevented from turning on said shaft 51 by the stud 53, which is stationary upon said plate 29, and then engages the notch 54 in the flange 55 of said sleeve as best shown in Fig. VI. Said sleeve 50 carries the cam 57, shown in Fig. V, which registers with the arcural arm 58 on the lever 59 shown in Figs. I and II which is fulcrumed on the screw 60 rigidly connected with said tone arm 6, and engaged with the lever 62 carried by the goose neck 63; which latter supports said sound box 5 and is fulcrumed upon a horizontal axis in the cross tube 64 of said tone arm 6, so that when said gear 48 is thrust into engagement with said gear 34, as above described, said cam 57 of the automatic feed mechanism, by frictional engagement with said lever arm 58, returns said tone arm 6 to its initial position indicated in Fig. I, and, while said tone arm is held in its initial position, predetermined by the aforesaid adjustment of the stop lever 14, said lever 59, being released by said cam 57, is returned to its normal position shown in Figs. I and II, by the weight of the sound box 5, which is as thus restored to operative position with respect to the sound record 9.

While said cam 57 is being turned, as above described, by engagement of the sleeve gear 48 with said motor gear 34, as above described, the cam 66, which is like a screw thread on said sleeve 50, bears upon the stud 67 projecting upwardly from said spring lever 32 so as to reset said spring lever 32 in engagement with the detent lever 31; the latter being constantly pressed toward the position shown in Fig. IV by its spring 69 which is secured upon said plate 29. Such movement places the spring 44 under tension, which tends to shift the clutch lever 45 in the direction opposite to that in which it was moved as above described; however, such movement is prevented by the unnotched portion of the sleeve flange 55 bearing upon the stationary stud 53, until the notch 54 in said flange registers with said stud 53; whereupon, said spring 44 snaps said lever 45 and the sleeve 50 and gear 48 into the inoperative position shown in Fig. III; such disengagement of the automatic feed mechanism gear 48 from the motor gear 34 being effected instantaneously when said sound box is lowered into its initial operative position indicated in Figs. I and II, as above described, the automatic feeding movement described having been effected in a few seconds by a single revolution of said sleeve 50.

Of course, in the position shown in the drawing, in which said gear 48 is withdrawn

from engagement with said gear 34, said cam 66 is out of engagement with said stud 67 of the spring lever 32, as shown, for instance, in Fig. IV. However, when said sleeve is shifted, toward the right in Fig. IV, to engage said gear 48 with said gear 34; such movement presses the cam 66 in position to contact with said stud 67 when the latter is in the position shown in Fig. IV; such movement of said sleeve being limited by the collar shown upon the right hand end of the stud shaft 51 in said figure.

It may be observed that an essential element of the embodiment of my invention above described is a bell crank lever having an arm of manually variable extent; *i. e.*, the lever 22 having the arm 23.

I do not desire to limit myself to the precise details of construction and arrangement of my invention herein set forth as it is obvious that various modifications may be made therein without departing from the essential features thereof as defined in the appended claims.

25 **I claim:**

1. In automatic feed mechanism for talking machine sound boxes; the combination with a sound record turn table; of a motor arranged to turn said table; a sound box including a vibratory diaphragm; means pivotally supporting said box for oscillation toward and away from the axis of said turn table; a stylus carried by said box, arranged to traverse a groove in a record on said table; a terminal stop member limiting the movement of said box toward the axis of said table; means arranged to raise said box from said terminal position, shift it away from the axis of said table, and lower it to its initial position, including a rotary cam; driving mechanism for said cam; means including a detent for said driving mechanism, normally preventing rotation of said cam; and means operatively connecting said de-

45 tent and terminal stop member, whereby movement of the latter caused by movement of said box, toward its terminal position, releases said detent and permits said driving mechanism to operate to return said box to its initial position.

2. In automatic feed mechanism for talking machine sound boxes; the combination with a rotary sound record; of a motor arranged to turn said record; a sound box; a stylus carried by said box arranged to traverse a groove in said record; a terminal stop member, limiting the terminal position of said box; means arranged to raise said box from said terminal position, and return it to its initial position, including a cam; driving mechanism for said cam; means including a spring pressed detent for said driving mechanism, normally preventing rotation of said cam; and means operatively connecting said detent and terminal stop

member, whereby movement of the latter, caused by movement of said box toward its terminal position, releases said detent and permits said driving mechanism to operate to return said box to its initial position.

70

3. In a sound reproducing mechanism; the combination with means to turn a sound record; of a sound box having means to cooperatively traverse such a record; feed mechanism arranged to automatically return said box from its terminal position to its initial position, including a motor with means to turn said record, and a driving gear arranged to be actuated by said motor; a stationary shaft; a sleeve carrying a gear adapted to be engaged and disengaged with respect to said driving gear, by axial movement on said shaft; means including a single spring arranged to shift said sleeve alternately in opposite directions; said spring being operatively connected with said sleeve by a lever; a cam carried by said sleeve, arranged to slide said sleeve to set said spring to disengage said gears; a lever detent arranged to normally detain said sleeve in the position in which it is set by said cam; and means, operative by the movement of said sound box toward its terminal position, arranged to release said detent; whereby such movement of said box effects the engagement of said gears to actuate said feed mechanism.

4. In a sound reproducing mechanism; the combination with means to turn a sound record; of a sound box having means to cooperatively traverse such a record; feed mechanism arranged to automatically return said box from its terminal position to its initial position, including a motor with means to turn said record, and a driving gear arranged to be actuated by said motor; a stationary shaft; a sleeve carrying a gear adapted to be engaged and disengaged with respect to said driving gear, by axial movement on said shaft; means including a single spring arranged to shift said sleeve alternately in opposite directions; a cam carried by said sleeve, arranged to slide said sleeve to set said spring to disengage said gears; a detent arranged to normally detain said sleeve in the position in which it is set by said cam; and means, operative by the movement of said sound box toward its terminal position, arranged to release said detent; whereby such movement of said box effects the engagement of said gears to actuate said feed mechanism.

5. In a sound reproducing mechanism; the combination with means to turn a sound record; of a sound box having means to cooperatively traverse such a record; feed mechanism arranged to automatically return said box from its terminal position to its initial position, including a motor with means to turn said record, and a driving gear arranged to be actuated by said motor;

130

a stationary shaft; a sleeve carrying a gear adapted to be engaged and disengaged with respect to said driving gear, by axial movement on said shaft; means including a single spring arranged to shift said sleeve alternately in opposite directions; whereby said sleeve gear is alternately engaged with and disengaged from said driving gear; and means arranged to prevent rotation of said sleeve when said gears are disengaged, including a stationary element arranged to be then engaged, by said sleeve, by axial movement of said sleeve on said shaft.

6. In a sound reproducing mechanism; the combination with means to turn a sound record; of a sound box having means to cooperatively traverse such a record; feed mechanism arranged to automatically return said box from its terminal position to its initial position, including a motor with means to turn said record; a driving gear; a gear mounted for axial movement to and from engagement with said driving gear; means, including a single spring, arranged to shift 20 said axially movable gear, alternately in opposite directions, but normally tending to engage said gears; and means arranged to set said spring to disengage said gears, including a cam axially movable with said 25 axially movable gear, a lever arranged to connect said cam and spring, and a detent for said lever; and means arranged to be shifted by the movement of said sound box

toward its terminal position, to release said detent and permit said spring to automatically engage said gears.

7. In a sound reproducing mechanism; the combination with means to turn a sound record; of a sound box having means to cooperatively traverse such a record; feed mechanism arranged to automatically return said box from its terminal position to its initial position, including a driving gear; a gear mounted for axial movement to and from engagement with said driving gear; means, including a single spring, arranged to shift said axially movable gear, alternately in opposite directions, but normally tending to shift said gear in one direction; and means arranged to set said spring to shift said gear in the opposite direction, including a cam axially movable with said axially movable gear, means including a detent arranged to detain said axially movable gear in idle position; and means arranged to be shifted by the movement of said sound box toward its terminal position, to release said detent and permit said spring to automatically engage said gears.

In testimony whereof, I have hereunto signed my name at Philadelphia, Pennsylvania, this nineteenth day of April, 1918.

EDWARD A. ESCHINGER.
